DUSTER AND METHOD OF MAKING SAME

Ralph Yutts, Miami, Fla.

Original application July 2, 1931, Serial No. 548,412. Patent No. 1,836,102. Divided and this application October 29, 1931. Serial No. 571,926

2 Claims. (Cl. 300—21)

This invention relates to certain new and useful improvements in dusters and method of making same, and is a division of co-pending application filed on July 2, 1931 by Ralph Yutts, Serial Number 548,412, which has matured into Patent No. 1,836,102.

The primary object of the invention is to provide a novel method in the manufacture of paper or fabric dusters especially designed for use in barber shops, beauty parlors and similar establishments for brushing or dusting the necks and faces of persons and being extremely inexpensive to produce, may be discarded after a single service operation.

15 A further object of the invention is to provide a brush or duster especially designed for use in barber shops wherein the brush or duster is formed of an elongated strip of paper foldable in the direction of the longitudinal axis thereof to provide superposed plies with corresponding edges of the plies slit to provide bristles while the opposite unslit edges are bunched into form for attachment to a handle.

25 With the above and other objects in view that will become apparent as the nature of the invention is better understood, the same consists of the novel method for expeditiously producing the duster and the duster per se.

In the drawing:—

30 Figure 1 is a perspective view showing an elongated strip of material folded in the direction of the longitudinal axis thereof to provide superposed plies for forming the brush or duster element;

35 Figure 2 is a perspective view similar to Figure 1, showing corresponding longitudinal edges of the superposed plies slit inwardly to provide bristles or wisps;

40 Figure 3 is a vertical cross-sectional view taken on line 3—3 of Figure 1; and

45 Figure 4 is a side elevational view of the slit plies bunched into brush or duster head formation and so retained by a cord associated with the unslit edges of the plies;

50 While the present invention may be used in any art where brushes or dusters are employed, the same is primarily intended for use in barber shops and beauty parlors as a duster for removing hair from the face and neck of a person following the cutting of the hair, the object being to discard the duster element after use thereof upon one patron. The duster element may be constructed of any suitable material, it being preferable to use paper of either the plain or crinkled type, the duster being

formed of any elongated strip of paper that is foldable in the direction of the longitudinal axis of the strip to provide superposed plies 15 as shown in Figures 1 to 3. Corresponding edges of the plies 15 as shown in Figures 2 and 12 ⁶⁰ are slit inwardly as at 16 to provide fibres, wisps or bristles 17. The unslit edges 18 are then crimped or folded in any preferred manner to provide a stock 19 and are so retained by a tying cord 20 or other fastening means, the ⁶⁵ brush of duster head as shown in Figure 4 being then ready for attachment to a handle. The slitting of the edges of the superposed plies may be accomplished after the strip has been folded to provide the superposed plies, or said strip ⁷⁰ before folding may be slit upon one longitudinal edge thereof.

The particular method employed consists of folding the elongated strip in the direction of length thereof, instead of on the line of the longitudinal axis, as by the longitudinal folding, it is possible to obtain any number of plies desired with each ply having a longitudinal edge free of folds and ready for slitting to produce the bristles or wisps. The ends of the folded strip as illustrated in Figures 1 and 2 are illustrated as confined within an end fold, but the strip may be otherwise folded with the ends exposed, the novel method, as stated, residing in ⁷⁵ the elongated strip being folded in the direction of the length or longitudinal axis thereof to provide the superposed plies. There is no nesting or telescoping arrangement, each ply being independent except for the end connections with ⁸⁰ other plies, the longitudinal edges of the plies being entirely separated, the slit edges forming the duster and the opposite unslit edges constituting a stock for attachment to a handle or a handle shank. The material of the duster ⁸⁵ may be fibre or paper, either plain, pleated or crepe or crinkled, and the slit plies are moved into duster formation in any preferred manner, as by folding, bunching, crimping, pressing or pleating.

100 I claim:—

1. The method of making a duster comprising the taking of an elongated strip of material and folding the same on a plurality of spaced transverse lines in the direction of the longitudinal axis of the strip to form superposed plies with the longitudinal edges of the plies unconnected from each other, slitting corresponding side edges of the plies to provide bristles and moving the other unslit unconnected ¹⁰⁵ ¹¹⁰

edges of the plies into form for attachment to a handle.

2. The method of making a duster comprising the taking of an elongated strip of material and 5 folding the same by movements in the lengthwise direction thereof to form superposed plies being free of folds and unconnected at opposite

side longitudinal edges thereof, slitting corresponding side edges of the plies to produce wisps and then bunching the unslit unconnected edges of the plies into stock form for attachment to a handle.
